JAMES W. DES CHAMPS, OF SUMTER, SOUTH CAROLINA

PUMP

Application filed February 18, 1929; Serial No. 340,795.

This invention relates particularly, though not exclusively to the pumping of deep oil wells.

In the pumps at present in use, the column 5 of oil in the well is lifted and lowered a distance equal to the stroke of the pump, at each reciprocation of the pump. The lowering of the column on the down stroke of the pump is a loss of energy for the equivalent of this 10 same column must be lifted on this next up-stroke.

The objects of this invention are to eliminate the feature of repeatedly lowering the column of pumped liquid after each active 15 pumping stroke and to provide simple, practical means readily applicable to existing pumping systems for accomplishing this desirable result.

The invention involves a number of special 20 novel features of construction, combinations and relations of parts as hereinafter described and broadly claimed.

The drawings accompanying and forming part of the specification illustrate one practical 25 commercial embodiment of the invention, but it should be understood that the structure may be modified as regards this particular disclosure without departure from the true spirit and broad scope of the invention.

30 Fig. 1 is a broken and part sectional side elevation of a length of well tubing carrying the pump structure and above that the new automatic valve for supporting and preventing the retrograde movement of the column;

35 Fig. 2 is an enlarged broken sectional view showing the new holding valve as seated in its operative relation; Fig. 3 is a similar view but showing the new valve structure as being run into the tubing and before seating there-

40 in; Figs. 4, 5 and 6 are cross-sectional views of the structure as on substantially the planes of lines 4—4, 5—5, 6—6 of Figs. 2 and 3.

In the illustration, the working barrel is shown at 7, the plunger operating therein is indicated at 8, and the upper and lower valves are shown at 9 and 10 respectively. The plunger is reciprocated by a valve rod 11 to which is connected a polished rod 12 or the sucker rods or line. The working barrel is 45 connected with the tubing 13; in the present

disclosure by a special collar 14 constructed to form a seat for the new valve mechanism, which supports the column of liquid raised by the pump.

The supporting valve mechanism is shown 55 in the present disclosure as consisting of a plurality of valves 15, cooperating with seats 16 at the upper ends of passages 17 cored or otherwise formed in the plug or body member 18 engaged on the upper end of the valve 60 rod. The valve rod is shown as having a shoulder 19 bearing on the cages 20 over the supporting valves 15, so as to force the plug structure down behind the pump mechanism when the latter is lowered into the working 65 barrel. The valve rod, however, has free sliding movement through this plug construction, so that the latter does not interfere with the pumping movements.

The plug structure which carries the supporting valves is locked in its proper relation above the working barrel by special means shown in the illustration as a set of three dogs 21 operating in radial guideways 22 in an expander sleeve 23. This expander 75 sleeve is slidably mounted on the reduced lower end portion 24 of the plug body and is shown as having a tapered upper end portion 25 engaging within a correspondingly tapered split expanding ring 26 carrying lead 80 or other suitable packing 27 for sealing engagement with the inner wall of the collar 14. The body of this packing ring is shown as having an internal flange 28 working in a retainer groove 29 in the body of the plug 85 so that it will travel with the plug but be free for expanding or contracting movements.

The supporting dogs 21 are forced outwardly by suitable means, such as the springs 90 shown at 30 seated in cavities 31 in the body of the plug and bearing against plates 32 on the backs of the dogs.

The dogs are forced inward and held in the retracted relation shown in Fig. 3 by the 95 surrounding walls of the tubing and the collar 14 and come into action to support the plug and valve structure only when in alignment with the enlargement 33 in the collar 14, in which relation of the parts they 100

are forced outwardly by the springs 30 and rest upon the shoulder 34, as shown in Fig. 2. When so seated, the expander ring becomes anchored to the collar 14 and hence any further lowering movement of the plug structure has the effect of forcing the packing ring down over the taper of the expander and hence expanding the packer into sealing engagement with the collar. This final movement for expanding the packer takes place after the pump structure is positioned in the working barrel and the shoulder 19 on the valve rod enables the plug to be forced down solidly enough to fully expand the packer and thus seal the valve structure within the supporting collar. The pump may thereafter be operated without disturbing the plug and its valve mechanism.

The valve rod is suitably sealed where it passes through the plug, the means for this purpose being shown as the packing 35 surrounding the rod at the lower end of the plug and yieldingly held by washer 36 engaged by spring 37 supported by a gland nut 38, which is secured by a lock nut 39. This form of yielding packing will automatically take up the wear resulting from the action of the pump rod.

To prevent the dogs from exerting any thrust on the expander ring while the apparatus is being lowered in the tube, the plates 32 at the backs of the dogs are shown as engaging at the top with the upper walls 40 of the cavities 31 when in the retracted relation shown in Fig. 3. Thus the rubbing thrust of the dogs against the inner wall of the tubing and collar is transferred to the body of the plug rather than to the expander ring when the plug is being lowered to its seat, but this upper shoulder 40 is cut away at the outside as indicated at 41, so that when the dogs spring outward as in Fig. 2, the plug may have the necessary further downward sliding movement to enable the expander ring to seal the packing against the inside of the collar.

The upper end of the seating cavity 33 in the collar 14 is shown as bevelled as at 42, so as to allow the dogs to emerge gradually as they reach this cavity and so as to act as an inclined guide to force the dogs inwardly when the plug is to be removed. In this removing operation, the pump structure will first be lifted in the working barrel and the continued lifting movement will then pick up the plug. The first upward strain on the plug will break the seal between the packing and collar and this first movement of the plug breaks the engagement between the packing ring and expander, thereby leaving the packing free to contract. The further movement causes the stop collar 43 screwed on the lower end of the plug to pick up the expander ring and the dogs, the bevelled shoulder 42 forcing the dogs inward and en-

abling the structure to be completely withdrawn substantially in the condition illustrated in Fig. 3.

With the invention installed above the pump, it will be seen that the weight of the column of liquid in the tubing is entirely taken off the upper pump valve on the lowering stroke of the pump, leaving a partial vacuum or lowering of pressure on the upper pump valve, so that the same opens more freely to admit the oil or other liquid above the same. The supporting valves 15, with their passages 17 about the valve rod are designed to pass without obstruction the full pump flow, so that they offer no resistance on the lifting stroke of the pump. The pump thus operates more freely, requires less power and can be worked more rapidly than with the present arrangements. The apparatus is of relatively simple inexpensive construction, sturdy in design and can be readily applied to existing forms of pumps. It is lowered through the tubing with the pump and takes its seat automatically in proper relation above the pump. With this invention leakage of the pump valves is not so serious as heretofore, because the liquid lifted by the pump is held and can not run back through leaking pump valves on the return stroke of the pump. The liquid is not churned by a lowering column of liquid at each downstroke of the pump and because of this same fact, the pump action is smooth and even. The collar which provides the seat for the plug and valve mechanism is readily connected to the tubing above the working barrel and does not interfere with the pump operations even though the packer and valve mechanism may not be used in conjunction with the pump.

What is claimed is:

1. An attachment for oil well pumps, comprising a collar attachable in a line of well tubing above the working barrel of a pump, said collar having an enlargement and a seat therein, a plug adapted to be lowered through the tubing into said collar, a normally retracted support for said plug, said support being shiftable into said enlargement and into engagement with the seat in the collar, packing on the plug, an expander for said packing operable by said support upon engagement of the latter with the seat in the collar and upwardly opening valve means carried by said plug.

2. An attachment for oil well pumps, comprising a collar attachable in a line of well tubing above the working barrel of a pump, said collar having an enlargement and a seat therein, a plug adapted to be lowered through the tubing into said collar, a normally retracted support for said plug, said support being shiftable into said enlargement and into engagement with the seat in the collar, packing on the plug, an expander

- for said packing operable by said support upon engagement of the latter with the seat in the collar, upwardly opening valve means carried by said plug, said plug having a passage therethrough for a pump valve rod or the like and packing at the lower end of the plug surrounding such passage for holding the liquid raised by the pump.
5. A liquid column supporting attachment for oil well pumps, comprising a plug having a passage for a pump valve rod and valved oil passages about said rod passage, an expandible packer on said plug, an expander sleeved on said plug, outwardly thrust supporting dogs for the plug, said dogs having a shifting movement relative to the plug and engageable with said expander for shifting the latter.
3. A liquid column supporting attachment 10 for oil well pumps, comprising a plug having a passage for a pump valve rod and valved oil passages about said rod passage, an expandible packer on said plug, an expander sleeved on said plug, outwardly thrust supporting dogs for the plug, said dogs having a shifting movement relative to the plug and engageable with said expander for shifting the latter.
4. A liquid column supporting attachment 15 for oil well pumps, comprising a plug having a passage for a pump valve rod and valved oil passages about said rod passage, an expandible packer on said plug, an expander sleeved on said plug, outwardly thrust supporting dogs for the plug, said dogs having a shifting movement relative to the plug and engageable with said expander for shifting the latter and a collar connectible in a line of well tubing and chambered to receive the 20 out-thrust supporting dogs and shouldered to provide a seat for said dogs.
5. A liquid column supporting attachment 25 for oil well pumps, comprising in combination a pump structure and a plug structure adapted to be lowered down through a line of well tubing, said plug structure having a passage for a valve pump rod or the like and an oil passage provided with an upwardly opening valve, an expandible packer carried by 30 said plug, a support for the plug, said support adapted for movement relative to the plug and an expander for the packer operable by said support in the movement of the same relative to the plug.
45. 6. A liquid column supporting attachment for oil well pumps, comprising a plug structure adapted to be lowered down through a line of well tubing, said plug having a passage for a valve pump rod or the like and an oil passage provided with an upwardly opening valve, an expandible packer carried by 50 said plug, a support for the plug, said support adapted for movement relative to the plug, an expander for the packer operable by said support in the movement of the same relative to the plug, said support including an outwardly thrusting dog adapted to be held in repressed relation by the surrounding walls of the tubing and a member carried by the tubing chambered to receive said dog and to form a seat for the same.
55. 7. A liquid column supporting attachment for oil well pumps, comprising a plug structure adapted to be lowered down through a line of well tubing, said plug having a pas-
- sage for a valve pump rod or the like and an oil passage provided with an upwardly opening valve, an expandible packer carried by said plug, a support for the plug, said support adapted for movement relative to the 70 plug, an expander for the packer operable by said support in the movement of the same relative to the plug, said support including an outwardly thrusting dog adapted to be held in repressed relation by the surrounding walls of the tubing and a member carried by the tubing chambered to receive said dog and to form a seat for the same, said chambered member having a bevelled face to force back the supporting dog when a lifting force is applied to the plug.
8. In combination with well tubing and a valved pump at the lower end of the same, a plug carrying a packer and insertable through the well tubing into position above 85 the valve mechanism of the pump, upwardly opening valve means carried by said plug, an extensible and retractable support having a seat in the plug, said seat having a shoulder for carrying upward thrusts of the support 90 during lowering movement of the plug in the tubing and said shoulder being relieved to enable upward movement of the support when said support is projected, an expander for the packer operable by the projected support in its upward movement relative to the 95 plug and a seating member for the plug, said seating member being carried by the tubing and chambered and shouldered to permit the projection of the support and to provide a 100 seat therefor.
9. In combination, a collar attachable in a line of well tubing, said collar having an internal seat, a plug structure having a passage and a stuffing box for a pump rod and adapted to be lowered on a pump rod down into position in said collar, expandible packing on said plug, a slidable sleeve on said plug for expanding said packing, a radially shiftable dog seated in the plug and engageable with 105 the sleeve, the seat for said dog being formed to hold the dog against packing expander movement of the sleeve, while the dog is retracted and to release the dog for packing expander movement when the dog is projected into the internal seat in the collar, upwardly opening valve means on the plug structure and a pump rod having a shoulder to drive the plug body downwardly relative to the expander sleeve when the dog is projected to support the latter in the collar.
110. 10. In combination, a collar attachable in a line of well tubing, said collar having an internal seat, a plug structure having a passage and a stuffing box for a pump rod and adapted to be lowered on a pump rod down into position in said collar, expandible packing on 115 said plug, a slidable sleeve on said plug for expanding said packing, a radially shiftable dog seated in the plug and engageable with 120 the sleeve, the seat for said dog being formed to hold the dog against packing expander movement of the sleeve, while the dog is retracted and to release the dog for packing expander movement when the dog is projected into the internal seat in the collar, upwardly opening valve means on the plug structure and a pump rod having a shoulder to drive the plug body downwardly relative to the expander sleeve when the dog is projected to support the latter in the collar.
125. 11. In combination, a collar attachable in a line of well tubing, said collar having an internal seat, a plug structure having a passage and a stuffing box for a pump rod and adapted to be lowered on a pump rod down into position in said collar, expandible packing on 130 said plug, a slidable sleeve on said plug for expanding said packing, a radially shiftable dog seated in the plug and engageable with

- the sleeve, the seat for said dog being formed to hold the dog against packing expander movement of the sleeve, while the dog is retracted and to release the dog for packing expander movement when the dog is projected into the internal seat in the collar, upwardly opening valve means on the plug structure and a pump rod having a shoulder to drive the plug body downwardly relative to the expander sleeve when the dog is projected to support the latter in the collar, the seat in the collar having an inclined portion for positively retracting the dog upon lifting movement of the plug structure.
- 10 11. In combination, well tubing having an internal shoulder, a pump operable in said tubing and a plug structure for supporting the column of liquid above the pump and comprising a plug body having a passage for the pump operating rod and an upwardly opening valved passage for the liquid lifted by the pump, an expandible packer carried by the plug body and means for expanding said packer including an operating dog engageable with the shoulder of the well tubing.
- 20 25

In testimony whereof I affix my signature.
